SOUND EMITTING APPARATUS

Ernst Wilckens, Berlin-Lichterfelde, Germany,
assignor to N. V. Machinerie-en Apparaten
Fabrieken "Meaf", Utrecht, Netherlands

Application February 1, 1934, Serial No. 709,396
In Germany June 15, 1933

3 Claims. (Cl. 177—7)

The present invention relates to improvements in sound emitting apparatus for the transmission of signals in air or water. One of the objects of the invention is to increase the efficiency in the 5 operation of such apparatus. Another object is to improve the sound emitted by such apparatus, while still other objects reside in overcoming various disadvantages of prior art constructions as will appear from the following detailed description, particularly when read in conjunction with the appended drawing in which:

Fig. 1 shows a load curve in dependence on the speed of a mechanically tuned oscillatory system without the use of a condenser; 10
Fig. 2 shows a load curve also dependent on the speed of an oscillatory system but with the use of a condenser connected in series or in parallel with the system according to the known manner;

Fig. 4 is a load curve obtained with the present invention, while

Figs. 3, 5 and 6 show wiring diagrams according to the invention.

For transmitting sound signals in air or water use is made of sound emitting apparatus which 25 consist substantially of a loud speaking telephone which is fed by single phase alternating current. In order to improve the efficiency of such sound emitters it is customary to tune the mechanical natural frequency of the sound producing 30 mechanical system to the sound frequency or to excite the sound producer with an alternating current whose frequency or alternating rate, depending on whether the sound producer is polarized or not, corresponds with the mechanical natural frequency of the diaphragm. This 35 operation can be best explained by a diagrammatic showing. The curve BC of Fig. 1 designates the electric load reception of the sound emitter dependent on the frequency n of the feeding alternating current or on the angular velocity of the alternating current. This curve has a maximum value A at a certain frequency n_r , and this resonance point A is the point within which the sound emitter is preferably operated.

40 Notwithstanding this measure, the electric generator for the production of the alternating current is inefficiently utilized, as the sound emitter along forms an inductive load for the generator and thus requires the generator also to produce 45 the wattless current portion. In order to overcome this defect, condensers have already been interposed in the circuit of the sound emitter.

In known arrangements, which operate with condensers in the circuit of the sound emitter 50 for improving the load factor (see German Patent

348,127) the condensers are so constructed that, in addition to the tuned mechanical system, a tuned electric circuit is also present. The result of coupling these two systems is that the load curve no longer has a maximum value in the operative point of the emitter, as in the arrangement without condensers (Fig. 1), but two closely adjacent maximum values which are grouped about the operative point A (Fig. 2). This variation of the load curve is intentionally striven for 10 by the originators of the known devices for the purpose of expanding or broadening the resonance point or crest of the curve and to improve the constancy of the angular velocity of the generator. Although an expansion of the curve form 15 is obtained by the interposition of a series or parallel condenser, the desired increase in the constancy of the angular velocity does not take place. In addition, this construction incurs the defect that as a result of the coupling between the electrical and mechanical oscillatory circuits unforeseen vibrating and quavering sounds arise which 20 distort the character of the sound and impair the sound effect. The following considerations will serve to confirm the fact that an improvement in 25 the constancy of the angular velocity is not attained.

An emitter without condensers (Fig. 1) produces its greatest sound performance in the point A of the load curve, for which reason in practice 30 it is generally operated at this point. However, if variations in the angular velocity now arise in the engine driving the generator that produces the alternating current, which variations cause a frequency variation of the operative frequency 35 n_r , it can be seen from Fig. 1 that a decrease in angular velocity and a resulting change of frequency from n_r to n_1 also takes off the load of the generator, which opposes the reduction in the angular velocity. An increase in the angular velocity, on the other hand, and the resulting change of frequency to n_2 causes unloading of the generator and a further increase in the angular velocity. Thus, the branch AB of the curve of Fig. 1 opposes variation in the angular velocity 40, 45 and thereby reduces the drop of angular velocity, while the branch AC of the curve of Fig. 1 supports a change of the angular velocity and an increase thereof.

In the curve according to known arrangements 50 as shown in Fig. 2, which employ condensers in the electric circuit, the same occurrence takes place, but in the reverse direction, as the operative point A does not lie at a crest of the curve but, as a result of the coupling of a mechanical 55

with an electrical oscillatory system, in a trough of the double-wave curve, so that at decreasing variation in the angular velocity the branch AB shows an increase of load and therewith an increase in the drop of angular velocity, while at increasing angular velocity the branch AC is connected with an increase of load and thereby with an action which tends to decrease the angular velocity.

10 In practice increasing as well as decreasing variations of angular velocity arise in the same degree. The curve in Fig. 2 is also attained only when concordance, that is, resonance, exists between the mechanical sound producer and the electrical oscillatory system consisting of machine self-inductance, emitter self-inductance and condenser. However, just in this condition the emitter is easily affected by the energy stored up in the electrical oscillatory circuit, so that, 15 as a further defect, vibrations arise in the emitter sounds, corresponding to the difference in the electrical and mechanical coupling frequency point B and C. The emitter sound is then superimposed or accompanied by a low frequency, 20 while the load amplitude fluctuates periodically. The constructional elements of the emitter are easily subject to excess strain which may result in injury to the emitter.

In another known apparatus, in which the 30 sound producer is excited by a static frequency transformer, condensers and choke coils of certain dimensions are interposed in the circuit of the sound emitter, in order to make certain paths permeable only for the basic frequency of 35 the feeding alternating current and other current paths only for an upper frequency (harmonic) of the alternating current (see British Patent 297,092). The load curve is hereby likewise unfavorably influenced, as it is dependent 40 on the saturation of the static frequency transformer as well as on the chokes, etc. also present in the electric circuit. The originators of 45 this known arrangement never recognized the influence and importance of the load curve.

45 The invention, on the contrary, is based on the correct knowledge of the significance which the course or form of the load curve has for the sound emitting apparatus. The object of the 50 invention is to construct a sound emitting apparatus having favorable properties relative to the form of its load curve as well as with respect to the electric load factors. The invention thus relates to a sound emitting apparatus consisting of a generator for alternating current of the 55 frequency n , a diaphragm sound producer, whose mechanical oscillatory structure has a natural frequency equal to twice the frequency n of the alternating current supplied by the generator and whose excitation coil is supplied with the 60 alternating current of the frequency n produced by the generator, and of an additional capacitative load of the generator for improving the load factor, which is so dimensioned that the curve indicating the electric load reception of the 65 sound producer in dependency on the frequency, retains its characteristic single-wave form at the operative point which it has without additional capacitative load.

70 According to one embodiment of the invention as shown in Fig. 4, the intended effect is attained in that, with the use of a condenser connected in parallel to the sound producer, the condenser C is dimensioned electrically so that the condition

is fulfilled between the self-inductance L of the emitter and the capacity C. In this case it is seen that a load curve exactly like Fig. 1 is obtained, thus offering the advantage that the load factor at the terminals of the generator 5 equals 1 while the form of the curve remains nevertheless unchanged and the operative frequency lies accordingly at the crest or apex A of the curve. At the same time, the generator is loaded only with an operative load, inasmuch 10 as in the case of resonance the apparent resistance of the condenser and of the emitter are equal, currents of equal magnitude flow in the emitter and condenser which, however, have a displacement of phase of 180°, so that the generator has therefore to furnish only the purely 15 operative current.

Examination of the load curve of the emitter outside of the operative conditions at still higher frequency discloses that a second maximum as 20 shown in Fig. 3 arises. This second maximum, at n_3 , results from the potential resonance between the parallel connected self-inductance of the emitter plus the natural self-inductance of the generator and the condenser connected parallel therewith. This second resonance has no unfavorable influence on the method of operation of the apparatus as it is far removed from the operative frequency of the emitter, and the 25 form of the mechanical resonance frequency of the emitter is in no way changed by the second resonance apex. On the contrary, only by placing the two resonances such a great distance from each other is it made possible to avoid the variation of the load curve. At the same time, 30 all vibratory phenomena are hereby avoided, and damage to the emitter will not occur.

The same effect may be attained in a still more perfect manner by means of the connection according to Fig. 5. Here the condenser C_1 and the 35 emitter inductance are first tuned to the operative frequency. By this parallel connection the condenser plus the emitter thus act only as an ohmic resistance. According to the invention the condenser C_2 is electrically dimensioned so 40 that for the operative frequency it comes in resonance with the inductance of the generator G. Experiment has shown that in this case also a 45 resonance curve according to Fig. 1 is produced. However, the additional advantage is also obtained that the generator G is loaded with rapidly 50 increasing current, which produces a particularly favorable load in consideration of the reduced excitation of the alternating current generator. If instead of a stationary generator G use is made 55 of a frequency transformer, this last connection can be used to advantage, as the load of a frequency transformer can be greatly increased with a rapidly increasing load factor. In the foregoing connections for the purpose of favorable 60 tuning, the resonance circuits are also provided with tuning means (variable choke coils or the like) as shown in Fig. 6, in order to make convenient manual adjustment possible.

I claim:

1. Sound emitting apparatus consisting of a generator for alternating current, a tuned diaphragm sound producer whose excitation winding is supplied with the alternating current furnished by the generator, and an additional capacitative load of the generator connected in parallel to said excitation winding, said load being so dimensioned that the curve indicating the electric load reception of the sound producer dependent on the frequency retains its characteristic single- 75

wave extent in the operative point, which extent said curve possesses without said additional capacitative load.

2. Sound emitting apparatus according to
5 claim 1, said capacitative load comprising a con-
denser, the capacity C of said condenser being
so dimensioned that it complies, together with
the inductivity L of the excitation winding of the
emitter, with the resonance requirement $n^2LC=1$.
10 3. Sound emitting apparatus according to
claim 1, said capacitative load comprising a con-

denser being so dimensioned that it complies, to-
gether with the inductivity L of the excitation
winding of the emitter, with the resonance re-
quirement $n^2LC=1$, and a second condenser con-
nected in series with the generator and said par-
allel connection of said first condenser with said
excitation winding of the transmitter, said second
condenser, together with the inductivity of the
generator, being tuned to the frequency of the
generator.
